(57) **CLAIM**

The ornamental design for a cleaning cloth, as shown and described.

DESCRIPTION

FIG. 1 is a perspective view of the top side of the cleaning cloth with multiple sections, the stippled portion illustrates a transparent strip overlaid onto a section of the cleaning cloth; FIG. 2 is a top plan view of the cleaning cloth illustrated in FIG. 1;

FIG. 3 is a left side view of the cleaning cloth illustrated in FIG. 1;

FIG. 4 is a bottom plan view of the cleaning cloth with all sections having a uniform color and contrasting textures not being claimed for the bottom;

FIG. 5 is right side view of the cleaning cloth illustrated in FIG. 1; and,

FIG. 6 is a front view of the cleaning cloth illustrated in FIG. 1.

The stippling is used to show a transparent strip overlaid on the cleaning cloth.
